UNITED STATES PATENT OFFICE.

GEORGE E. DOWNE, OF CHICAGO, ILLINOIS, ASSIGNOR TO THE AMERICAN RADIATOR COMPANY, OF NEW JERSEY.

DESIGN FOR A SECTION FOR VERTICAL HEATERS.

SPECIFICATION forming part of Design No. 33,233, dated September 18, 1900.

Application filed August 13, 1900. Serial No. 26,790. Term of patent 14 years.

To all whom it may concern:

Be it known that I, GEORGE E. DOWNE, a citizen of the United States of America, residing at Chicago, county of Cook, and State of Illinois, have invented and produced a new and original Design for a Section for a Vertical Heater, of which the following is a specification, reference being had to the accompanying drawings, forming a part thereof, and o in which—

Figure 1 is a plan view of the design; and Fig. 2 is a sectional view thereof, taken on the line of the arrows 2 2 of Fig. 1.

As shown in the drawings, the leading or 5 material features of the design consist of an annular cylindrical member A, having inner and outer and end walls, an annular cylindrical member B, occupying the axis of the

member A and having open ends, and radial partitions C, having top, bottom, and side 20 walls and uniting the members A B.

Minor features of the invention comprise annular flanges a a at each end of the section A and adjacent to its outer face and annular flanges b b at each end of the member B.

I claim as my invention—

The design for a section for a vertical heater, as herein shown and described.

In testimony whereof I have signed my 30 name to this specification in the presence of two subscribing witnesses.

GEORGE E. DOWNE.
